(57) **CLAIM**

The ornamental design for a horseshoe, as shown and described.

DESCRIPTION

FIG. 1 is a front elevation view of a horseshoe, showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is bottom plan view thereof;

FIG. 7 is a front-right perspective view thereof; and,

FIG. 8 is a rear-left perspective view thereof.

The broken lines in the drawings are used to illustrate unclaimed portions of the horseshoe and form no part of the claimed design.

1 Claim, 6 Drawing Sheets
